C. GORA.

COMBINED WEAPON AND WIRE CUTTER.
APPLICATION FILED JULY 5, 1918.

1,285,681.

Patented Nov. 26, 1918.

INVENTOR
Charles Gora.
BY Oscar Gora
his ATTORNEY

UNITED STATES PATENT OFFICE.

CHARLES GORA, OF ATHABASCA, ALBERTA, CANADA.

COMBINED WEAPON AND WIRE-CUTTER.

1,285,681.

Specification of Letters Patent. Patented Nov. 26, 1918.

Application filed July 5, 1918. Serial No. 243,371.

To all whom it may concern:

Be it known that I, CHARLES GORA, a subject of the Emperor of Austria, residing at Athabasca, Province of Alberta, and Dominion of Canada, have invented certain new and useful Improvements in Combined Weapons and Wire-Cutters, of which the following is a specification.

This invention relates to improvements in weapons, and has as its principal object the provision of a weapon which may be used as a gun or knife with equal facility, combined with which is a wire cutter of novel design.

15 A further object is to provide a weapon of the type described which is of neat appearance, and comprised of few and simple parts which are not readily liable to become disordered.

20 A still further object is to provide a new and improved form of gun operating means of simple construction.

These and other like objects are attained by the novel construction and combination 25 of parts hereinafter described and shown in the accompanying drawing, forming a material part of this disclosure, and in which:—

Figure 1 is a side view showing an implement made in accordance with the invention.

30 Fig. 2 is a broken edge view of the same.

Fig. 3 is an enlarged fragmentary sectional view taken through the handle and showing the wire cutter in a closed position.

Fig. 4 is a transverse sectional view taken 35 on line 4—4 of Fig. 2, and

Fig. 5 is an enlarged fragmentary side elevational view, showing the mechanism by which the gun is operated.

It will be obvious from inspection of the 40 drawing that the implements are intended for close or hand-to-hand engagement, the same being comprised of a handle 10, having an open slot 12 formed between its side portions. At the upper end of the handle is an integrally formed extension of frame 14 from which projects the gun barrel 15, provided with a fixed sight 16 as is usual.

Mounted in the recess formed in the frame 45 14 is a cylinder 18, rotatable upon the pin 19 or spindle 17, and having attached at the rear a ratchet plate 19, the cylinder being formed with a plurality of openings adapted to carry cartridges 20 of the usual type which may be brought into alignment with 55 the bore of the barrel 15.

The lock mechanism is located in a cham-

ber 22, rearward of the frame in which the cylinder 18 rotates at the upper end of the handle, and extending beyond the chamber 22, and also over a portion of the frame 14 60 is a rigid fixed knife blade 23, having cutting edges 24 on each side terminating in an acute point 25, the blade extending directly outward and in alignment with the handle element 10.

A cover plate 26 is fitted over the chamber 22, and held by screws or like securing means, engaging with the openings 27 so as to form a substantially dust proof chamber.

Rotatably mounted on the pin 28 fixed in 70 the side wall of the chamber, is an angular lever 30, the front extending portion 31 of which terminates in a sharp point 32, operable within a recess 33, formed in the front wall of the chamber, the point being adapted 75 to act as a hammer when detonating the cartridge 20, a stop shoulder 34 adjacent to the point being adapted to rest normally in a seat 35, formed in the casing of the chamber.

Also formed in this wall below the seat 80 35 is another recess 36 in which operates a dog 37, its point 38 being adapted to engage with the ratchet 19, whereby the cylinder is turned as the lever 30 is operated, the dog being pivoted to the lower end of the 85 lever on a pin 39, below the pin 28, so that as the hammer is raised the dog will actuate the cylinder into position to bring a new cartridge into register with the barrel 15.

This lever is normally pressed forward by a flat spring 40, secured in the chamber by a pin 41. Arranged substantially in alignment with the barrel 15 is a plunger 44 passing through the outer wall of the chamber. 95 This plunger is retractable by a ring 45, fixed upon its extending end, while within the chamber, fixed upon the plunger, is a collar 46, normally pressed inwardly by the coiled compression spring 47.

Carried on the extreme inner end of the plunger 44 is a pawl 48, pivoted on a pin 51 and held in operative engagement by a flat spring 52, the pawl being engageable within a V shaped recess 50, formed at the upper edge of the lever 30, the arrangement being such, that as the plunger is drawn outward from the chamber, the pawl 48, engaged with the lever, turns it outwardly, which action through the dog 37 rotates the cylinder, 105 bringing a new cartridge into position for 110 operation.

Full action of the plunger causes the point of the pawl 48 to come out from the recess, permitting the hammer to be forced against the cartridge by action of the spring 40, 5 the pawl turning on its pivot to reengage in the recess when the plunger is moved in.

Below the frame 14 is a fixed cutter or shear blade 55, extended at an angle, and pivoted in the slot 12 of the handle, on the 10 pin 56, is a lever 57, having a shear blade 58 formed on the part extending through a slot 59 in the handle, the longer operative end of the lever extending downward through the lower end of the handle, and is normally 15 pressed into operative position by a coiled compression spring 60, so that the shear blades 55 and 58 respectively are held in open position, and it will be obvious that when an article, as a strand of wire, is entered therebetween and the lever 57 is pressed inwardly, that the same will be sheared.

Rigidly secured in the uppermost end of the slot 12 is a relatively wide flat spring 62, engaging with the outer edge of the lever 57, 25 the spring having an inturned lower portion 63 terminating in a hook 64, which, due to the resiliency of the spring, is engageable within a recess 65, formed in the extreme bottom of the handle, thereby holding the 30 lever in a substantially closed position, as is shown in Fig. 3, the element 62 acting as a cover for the opening in the handle and also presenting a relatively broad surface for the hand when operating the lever 57. It 35 will be clear from Fig. 3, that a pressure exerted by the palm of the hand against the back of the vertical shank of the flat spring 62, pressing the same against the lever 57 will tend to release the catch 64 to permit 40 opening of the cutting jaw 58.

Having thus described my invention what I claim as new and desire to secure by Letters Patent, is:

1. In an implement of the class described, 45 the combination with a handle, a gun having a revolving cylinder secured transversely to said handle, a knife blade extending outward in alignment with said handle above said gun, and a wire cutter below said gun, 50 said wire cutter having a blade pivoted in the handle of the apparatus.

2. In a gun, the combination with a barrel, a cylinder adapted to carry cartridges adjacent to said barrel, a ratchet secured 55 upon said cylinder, a lever pivoted in a chamber rearward of said ratchet, a lever pivoted in said chamber, said lever having a hammer formed therewith and adapted to detonate a cartridge in said cylinder, a

dog pivoted to said lever, said dog being engageable with said ratchet whereby said cylinder is rotated, a plunger extending through the walls of said chamber, means for operating said plunger, means on said plunger for operating said lever whereby it may be retracted, and means for forcing said hammer forward.

3. In a gun, the combination with a handle, a barrel affixed thereto, and a revoluble cylinder adapted to carry cartridges adjacent to said barrel, of a chamber rearward of said cylinder, a ratchet plate secured at the rear of said cylinder, a lever pivoted in said chamber, a hammer formed with said lever adapted to make contact with cartridges in said cylinder, a dog pivoted to said lever opposite to said hammer, said dog being engageable with said ratchet whereby said cylinder may be rotated, a spring normally pressing said hammer forward, a plunger 80 slidable through the walls of said chamber, means for operating said plunger, means for normally pressing said plunger forward, a pawl pivoted on the inner end of said plunger, said pawl being engageable with a recess formed in said lever, whereby it may be retracted, and means permitting forward movement of said pawl so as to enter the mentioned recess.

4. In a gun operating mechanism, the combination with a handle, a chamber formed in the upper end thereof, a cartridge carrying cylinder rotatable in said chamber, and a barrel extending therefrom, of a ratchet secured to the end of said cylinder, a lever pivoted to rotate in said chamber, a hammer formed with said lever adapted to detonate cartridges held in said cylinder, a dog loosely pivoted to said lever on the opposite side of its pivotal point, said dog being engageable with said ratchet, a spring fixed in said chamber adapted to press said lever in one direction so as to cause said hammer to make contact with cartridges, a plunger 100 slidable in said chamber, having a part extending therebeyond, a ring secured to said plunger whereby it may be operated, a spring on said plunger forcing the same normally forward, a dog loosely pivoted on the inner end of said plunger, said dog having a part engageable within a recess formed in said lever whereby it may be retracted, and means permitting said dog to enter said recess without communicating motion to said lever.

In testimony whereof I have affixed my signature.

CHARLES GORA.
